(57) **CLAIM**

The ornamental design for an infant carrier with a three-
dimensional seat, as shown and described.

DESCRIPTION

FIG. 1 is a top, front, left side perspective view of the infant
carrier without the three dimensional seat insert being
exposed, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear, right side exploded perspective view of
the infant carrier of FIG. 1 wherein the infant carrier is
shown with the three dimensional seat insert;

FIG. 9 is a top, rear, right side perspective view of the infant
carrier of FIG. 1 showing an expanded head support portion
folded down into an alternate position; and,

FIG. 10 is a top, rear, right side perspective view of the
infant carrier of FIG. 1.

Any shading and cross-hatching shown in the drawings are
not features of the design, but are utilized to illustrate the
surface contours of the infant carrier design in the drawings.
